UNITED STATES PATENT OFFICE.

JOHN S. BRENNAN, OF MILWAUKEE, WISCONSIN.

GARBAGE AND RUBBISH INCINERATOR.

1,301,371.

Specification of Letters Patent. Patented Apr. 22, 1919.

Application filed April 10, 1918. Serial No. 227,695.

To all whom it may concern:

Be it known that I, JOHN S. BRENNAN, a citizen of the United States, and resident of Milwaukee, in the county of Milwaukee and 5 State of Wisconsin, have invented certain new and useful Improvements in Garbage and Rubbish Incinerators; and I do hereby declare that the following is a full, clear, and exact description thereof.

10 This invention refers to garbage and rubbish incinerators and has primarily for its object to provide a simple economical and sanitary device for the disposition of garbage, rubbish and the like.

15 A more particular object of the invention is to provide a device of this character separate from the chimney which can be placed at any convenient location in the basement and is connected with the kitchen or wherever desired by a receiving chute provided with connected means at its receiving and discharge ends to prevent odors and gases from escaping from the chute.

20 The invention in one practical form in which it may be embodied is illustrated in the accompanying drawing, in which:

A single view is an elevational view with parts broken away and in section to more clearly illustrate the details of the invention.

30 At the present time the most common forms of incinerators in use are of that type built into the chimney. This makes it impossible to install them in old residences as the chimney must be used as the receiving 35 chute for the refuse and, in most instances, is not in a convenient place or of sufficient size to permit such use.

Furthermore where it is possible to install this type of incinerator it requires considerable alterations in the chimney together 40 with the accompanying great expense. To overcome these disadvantages the present invention has been designed in which 1 designates a cylindrical receptacle preferably 45 made up in three sections and provided with a top 2 which has centrally thereof an aperture 3, mounted in which is a receiving chute 4 which extends upwardly through the floor 5 and communicates with the kitchen 50 or other convenient place desired. The receiving end of the chute 4 has hingedly connected thereto a cover 6 provided with side walls and a bottom extending downwardly into the chute which form a receiving hop- 55 per 7. Hinged to the top member 2 and

adapted to close the aperture 3 is a gate 8 that is connected to the lower part of the hopper 7 by means of a chain 9.

It will be seen that upon swinging the cover 6 outward to place refuse in the hopper 7 by means of the chain 9 connecting it to the hopper will be pulled upward thus closing the aperture 3 and preventing odors or gases which might arise from the contents of the receptacle to pass 65 up through the chute and into the room above.

The top 2 of the receptacle is further provided with a flue opening which is connected to the chimney or outer air by means of 70 a pipe 10. Adapted to fit in and cover the flue opening is a screen 11 that prevents paper or other light particles from passing through the aperture.

The central portion of the receptacle 1 75 forms the sides of the fire pot and is preferably cast with air passages formed in its sides to supply a large amount of air thus insuring perfect combustion of its contents. Positioned below the fire pot 12 and pivot- 80 ally connected to the sides of the receptacle is a grate 13 which is in linked connection with the lever 14 situated at the outer side of the receptacle. When the lever is in its upright position it will be seen that the links 85 connecting it with the grate are passed slightly over center and abut against the stop 15 thus locking the grate in its upward position. The lower section or dump pit is provided with the customary door 16 having 90 a slide therein to permit air for combustion.

In operation all rubbish and garbage is placed into the receptacle either through the receiving chute or the door 17 in the upper 95 portion of the receptacle. After being allowed to accumulate for a short period of time any excess amount of moisture contained in the refuse will be evaporated and carried out through the flue opening thus 100 leaving a combustible mass which can be readily ignited in any suitable manner.

After the contents of the receptacle has been consumed, any incombustible material such as tin cans, china ware and so on which 105 is not consumed will remain upon the grate. From there it can be dumped into the pit by tilting the grate and removed through the door 16.

What is claimed is:-

110

In an incinerator of the class described, a combustion chamber having a top provided with a central circular opening, a vertical receiving chute having its lower open end 5 coincident with said circular opening, the upper end being disposed laterally and having its inlet opening positioned vertically, a flue pipe communicating with said top between said central opening and the wall of 10 the combustion chamber, a cover hinged on the inlet end of the said chute at the lower edge of the opening thereof, a receiving hopper formed of a bottom and side walls and carried by said cover, said hopper bot-

tom closing the chute upon the opening of 15 the cover, a gate valve hinged to said chamber top at one edge of said central opening and movable to completely close the latter, and a flexible connection between said gate valve and the hopper bottom whereby said 20 valve and hopper bottom will simultaneously close the chute upon the opening of said cover.

In testimony that I claim the foregoing I have hereunto set my hand at Milwaukee, 25 in the county of Milwaukee, and State of Wisconsin.

JOHN S. BRENNAN.
